US00D977634S

(12) **United States Design Patent** (10) **Patent No.:** **US D977,634 S**
Powell et al. (45) **Date of Patent:** **** Feb. 7, 2023**

(54) **UNIT END CONNECTOR**

(71) Applicant: **Fisher & Paykel Healthcare Limited**,
Auckland (NZ)

(72) Inventors: **Kevin Blake Powell**, Auckland (NZ);
Mark Thomas O'Connor, Auckland (NZ); **Brent Ian Laing**, Auckland (NZ); **Jason Allan Klenner**, Auckland (NZ)

(73) Assignee: **Fisher & Paykel Healthcare Limited**,
Auckland (NZ)

(**) Term: **15 Years**

(21) Appl. No.: **29/789,941**

(22) Filed: **Oct. 26, 2021**

Related U.S. Application Data

(62) Division of application No. 29/703,953, filed on Aug. 30, 2019, now Pat. No. Des. 937,411.

(57) **CLAIM**

The ornamental design for a unit end connector, as shown and described.

DESCRIPTION

FIG. 1 is a rear, top, and left side perspective view of a unit end connector embodying our new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the unit end connector that form no part of the claimed design.

1 Claim, 7 Drawing Sheets
